(57) **CLAIM**

The ornamental design for a machine housing, as shown and described.

DESCRIPTION

FIG. 1 is perspective view from above and in front of the invention;

FIG. 2 is a rear elevational view of the invention;

FIG. 3 is a perspective view from the right of the invention;

FIG. 4 is a top view of the invention;

FIG. 5 is a perspective view from the left of the invention;

FIG. 6 is a perspective view from above and behind left of the invention; and,

FIG. 7 is a perspective view from behind and the left.

The invention is a housing for a large industrial machine. The broken lines in the drawings depict unclaimed environmental subject matter.
